SHIELDING OF CONVERTERS

Eugene J. Houdry, Rosemont, Pa., assignor to
 Houdry Process Corporation, Dover, Del., a
 corporation of Delaware

Application May 13, 1936, Serial No. 79,406

13 Claims. (Cl. 23—288)

The present invention relates to the operation and control of reactions, including those resulting from or involving the use of contact masses, whether catalytically active or substantially inert. It has special application to the type of operations where fluids are fed to a reaction chamber of a converter at a temperature which is substantially or widely different from the desired reaction temperature, as, for example, where it is desired to offset or compensate for the endothermic or exothermic character of the reaction by supplying the reactants at a temperature substantially above or below that of the reaction. In converters or similar apparatus employed to carry out such operations, portions of the apparatus with which the relatively cold (or relatively hot) fluid comes in contact, prior to entering the reaction chamber, tends to assume a temperature widely or substantially different from those portions of the apparatus which surround or are located in the reaction zone and therefore those parts or intervening parts of the apparatus normally suffer undesirable or severe internal stresses. In its general relation to the control of reactions, particularly those utilizing a contact mass to promote, enter into, or in any way effect reactions such as the synthesis of ammonia, the production of sulphuric anhydride, the treatment or transformation of hydrocarbons, etc., the present invention may be considered as an improvement upon or further development of Patent No. 1,987,904 issued to me on January 15, 1935.

In so far as the present invention relates to minimizing or preventing radiant heat exchange between a tube sheet or partition bounding the reaction chamber and other parts of the converter, such as the other walls of a manifolding chamber, it may be considered as a further development of the copending application of Thomas B. Prickett, Serial No. 14,068, filed April 1, 1935 (Patent No. 2,102,644, issued December 21, 1937). However, it will be seen that the present invention, as distinguished from the copending application, does not permit more than a very small percentage of the introduced fluid to sweep over the tube sheet or equivalent before entering the reaction chamber or distributing conduits which extend thereinto; also that the present invention provides heat baffles along or in spaced relation with the casing walls adjacent and opposite such tube sheet or the like or with other walls or surfaces with which relatively cold (or hot) fluids may come in contact before entering the reaction chamber.

It is a primary object of this invention to devise improved ways and means to minimize or restrict heat exchange between fluids and parts of a reaction or conversion apparatus before such fluids reach parts of the apparatus where it is desired to have heat exchange occur, thereby to reduce or eliminate substantial or deleterious thermal stresses which commonly occur in the casing walls or other elements of reaction apparatus. A further object is to employ baffling means which do not possess the undesirable characteristics of certain conventional heat insulating materials and do not tend to absorb large quantities of the fluid employed. Another object is to provide suitable mounting means which permit convenient removal and replacement of shielding members. Other objects and advantages will be apparent from the detailed description which follows and from the specification as a whole.

An understanding of the invention may be facilitated by reference to the illustrative embodiments thereof shown in the accompanying drawings in which:

Fig. 1 is an elevational view, partly in section, of a converter or reaction chamber having the central portion thereof cut away and having baffles or shields in both manifolding chambers;

Fig. 2 shows the lower end of a converter generally of the type shown in Fig. 1 having rather similar baffles but having a jacketed chamber surrounding the manifolding chamber;

Fig. 3 shows in somewhat enlarged scale the lower end of a converter similar to that shown in Fig. 1 but having multiple baffles shielding certain portions of the surfaces or walls which bound the manifolding chamber;

Fig. 4 is an enlarged detail view in section of a portion of the apparatus shown in Fig. 1;

Fig. 5 shows an enlarged detail view in section of a portion of the lower tube sheet of Fig. 1 with a modified construction of baffles, permitting convenient assembly of the baffles which shield the beams supporting the tube sheet;

Fig. 6 shows in detail an exemplary form which the lower ends of the baffles, shown in the lower manifolding chambers of Fig. 1 or 3, may take;

Fig. 7 is a developed section of a baffle plate of the type shown in Fig. 3, having slots therein to permit rapid assembly thereof on or adjacent surfaces which it is desired to shield;

Fig. 8 shows an enlarged detail view of a grooved post or stud of the type employed in Fig. 3 and a broken away section of the casing to which it is attached, such post being adapted

for use with a slotted sectional tube sheet, such as shown in Fig. 7;

Fig. 9 is an enlarged detail view in section taken on line *a*—*a* of Fig. 7 to further illustrate the slots of Fig. 7; and

Fig. 10 shows in cross-section a modified form of the ends of the baffles which are parallel with the tube sheet in Fig. 3.

Referring more in detail to the drawings, in the several figures of which like reference characters denote similar parts, 1 is a converter casing having a reaction chamber 2 bounded at either end by manifolding chambers 3 and 4. The lower manifolding chamber 3 is separated from the reaction chamber by the tube sheet 5 and the upper manifolding chamber is separated therefrom by tube sheet 6. Within the reaction chamber perforated conduits 7, which by way of illustration may be considered as inlet conduits, and perforated conduits 8, which may be considered as outlet conduits, are embedded in contact mass 9, which latter may consist of any known or desired contact materials, including silicates of alumina or clayey materials, e. g., blends of silica and alumina in fragmentary or preferably in molded form and with or without the addition of other active components such as metals and metallic compounds. Baffles 10 and 11 line the inner walls of manifolding chamber 3 in Fig. 1 and are in spaced relation with such walls. These baffle plates are preferably made of non-absorbent, corrosion-resistant material such as chrome steel or other metallic or durable material. Baffles 10 are suitably fastened in spaced relation to the walls of casing 1 as by fastening means or studs 12, which have shoulders or sleeves, and which are tapped into, welded or otherwise fastened thereto. The baffles are maintained in spaced relation with the wall of casing 1 by combined spacer and fastening means or spacer blocks 13, which may be fastened to the baffles but not to the walls of casing 1. The tube sheet baffles 11 are held in place, in spaced relation with tube sheet 5, by nuts 14 which are screwed onto the ends of the inserts or extensions to conduits 7. Sleeves 15, which surround each of such inserts, maintain baffles 11 in desired spaced relation with the tube sheet.

Baffles 10 in Fig. 1 are made up in sections which overlap on the studs 12 or spacer blocks 13, as shown in enlarged detail in Fig. 4. These joints may be held firmly together by nuts which engage suitable screw threads on the studs or inserts which pass through the spacer blocks, as shown in Fig. 1 but omitted for the sake of clarity in the detailed showing in Fig. 4.

Baffles 10a and 11a which surround the walls of upper manifolding chamber 4 are generally similar to those which surround the walls of lower manifolding chamber 3. Baffles 10a are ordinarily fastened to the casing walls at several points by studs 12a which are tapped into such walls while baffle 11a is supported by sleeves 15a which surround the inserts of conduits 8 and rest against tube sheet 6, nuts 16 being applied to the threaded ends of the inserts of conduits 8 to hold the parts in place.

In the operation of the apparatus reactants may be admitted to one of the manifolding chambers at a temperature above that of the reaction, if the latter is endothermic, or at a temperature very much below that of the reaction, if the latter is strongly exothermic. In either instance the shell of the converter and the partitions or tube sheets are to be protected from sharp tempera-

ture changes to avoid distortion and rupture of the apparatus. In some cases, as in the treatment and conversion of hydrocarbons, alternative endothermic and exothermic reactions take place due to the accumulation of a carbonaceous or other burnable deposit on the catalyst (during the on stream or endothermic reaction) which is removed by a subsequent regeneration by oxidation which is a strongly exothermic reaction. The on stream reaction temperatures are normally below regeneration temperatures and at times the difference is quite wide as from 150 to 500° F. and it is desirable to use cool reactants to control the exothermic reaction.

When reactants are introduced into manifolding chamber 3, they pass upwardly through inserts 1a of the double or nested conduits 1 and then emerge through perforations 7p into contact with mass 9. The fluid migrates through mass 9 to perforations 8p in conduits 8 and leaves the reaction chamber through inserts 8a which empty into manifolding chamber 4, from which latter the products of reaction may leave the converter. When cool reactants or regenerating fluid pass up through insert 1a of inlet conduits 7 and then pass downwardly through the annular space between insert 1a and outer perforated member 1b, heat exchange is effected with the surrounding mass which keeps the latter from rising to too high a temperature while the regeneration medium is brought up to such a temperature that the desired combustion or regeneration will be sustained in the reaction chamber 2. It is desirable that the heating up of the regeneration medium, which preferably takes place during its passage through the conduits 7, be accomplished in such a way that the regeneration medium will not cause any incidental deleterious cooling of the tube sheet 5 or other walls of the manifolding chamber 3. When casing 1 of the converter is made in one continuous piece, and special provision is not made for preventing cooling within the manifolding chamber 3, large stresses are set up in the casing, particularly just at or below the tube sheet 5, which tend to cause distortion or failure thereof. Baffles 10 of Fig. 1 counteract this cooling effect and, supplemented by insulation S which surrounds the exterior of the converter, tend to keep the walls of the latter, particularly portions at or below the tube sheet 5, up to at least approximately the temperature of the walls thereof above such tube sheet. Baffles 11, which extend along and adjacent to the tube sheet 5 and around supporting beams 16 prevent undesirable cooling of the tube sheet, thereby keeping the contact mass 9 which is adjacent such tube sheet from getting cooled below that of the main body of the mass and protecting supporting beams 16 from being cooled down to, for example, atmospheric temperature on their lower surface whereas the top of the beam may be at a temperature of approximately 800 or 900° F. Such temperature differences between the top and the bottom of a beam sets up tremendous stresses and tends to cause the beam to bow upwardly, thus dislocating the tube sheet and the conduits within the reaction chamber.

The principal purpose of baffles 10a and 11a, i. e. of baffles in both manifolding chambers, is to make the converter reversible in operation; that is, to permit relatively cool fluid to be introduced into manifolding chamber 4 whereas products of regeneration or the like may be withdrawn through manifolding chamber 3, as well as according to the manner described above.

The baffles are provided with small perforations or openings 17 to permit approximately 1 or 2% of the fluid which passes through the converter to circulate freely behind the baffle plates, thereby to avoid the possibility of accumulation of material or of explosion behind the same. Baffles 10 have openings or serrations 17 at their lower ends, as shown in Figs. 1 and 6, to permit the free drainage of any condensate which may 10 accumulate behind the baffles. Instead of having openings or serrated edges, the baffles may be slightly spaced from the casing.

In Fig. 2 the manifold chamber 3a is provided with a fluid-tight jacket 18 therearound. Heat 15 exchange fluid may be introduced into the jacketed chamber through conduit 19 and withdrawn therefrom through conduit 20, to supplement the action of baffles which are located within the manifolding chamber adjacent its walls. In this 20 embodiment, the baffles comprise continuous strips extending from the top of the manifolding chamber downwardly throughout the whole remaining extent of the casing walls thereof and along the neck 21, to project between the flanges 21a and 22, thereby extending the zone of protection. The ends of the baffles are made thinner than the gasket between the flanges 21a and 22 so as not to interfere at all with the making of a 25 fluid-tight joint and are provided with small openings 17b to permit a slight amount of circulation behind the baffles and to permit drainage of fluid therefrom. Baffles 11b adjacent tube sheet 5b are held in spaced relation therewith by studs or posts 23 which are tapped into the tube sheet 30 and which may be threaded at their outer ends to receive nuts 24.

In Fig. 3 a multiple heat baffling arrangement is shown for the parts of casing 1, which need the most protection, namely tube sheet 5c and the 40 supports therefor including beams 16c. Sectional baffles 10c extend along the whole side of the casing wall of the manifolding chamber to a point adjacent neck 21c of the converter, baffles 10d extend half or two-thirds of the way down 45 such casing, while baffles 10e extend over only a short section of the upper portions of such casing wall near the tube sheet 5c. Baffles 11c, 11d, and 11e are joined at their peripheries or edges with the upper ends of baffles 10c, 10d and 50 10e, respectively, to form approximately fluid-tight joints. A special form of such joints is illustrated in cross-section on an enlarged scale in Fig. 10 which shows slots or grooves on baffles 11c, 11d and 11e into which the upper ends of the 55 baffles 10c, 10d, or 10e may fit.

When a type of treating operation is contemplated which causes deterioration of the heat baffles and requires periodic replacement of the same, or when it is desired to facilitate the assembly of heat baffles within a converter, there is often an advantage to be gained by having the walls which are to be shielded provided with suitably demountable or slip connections. These 60 may comprise posts 25 (Fig. 8) having grooves 25a, or the equivalent, rigidly fastened to the wall to be shielded, for example the casing 1. Such posts will be disposed in regular arrangement to correspond with the spacing of slots such as 26 in baffle 27 shown in Fig. 7. Baffles 10c, 65 10dd and 10e in Fig. 3 may be like or similar to the developed section shown in Fig. 7. Post 25 is provided with three grooves as shown, making it suitable for use in the multiple baffles disclosed in Fig. 3. A baffle section 27 may be mounted 70 in Fig. 3 by lining up the large portions 26a of the slots 75

26 with the top of posts 25, pushing baffle 27 down over the posts until the appropriate depressions or grooves 25a are reached and then moving the section 27 transversely so that the narrow parts 26b of the slots 26 will become tightly engaged in the grooves 25a of posts 25. Likewise, in removing the baffle sections, all that need be done is to move each section slightly to the right or left, depending on which way the small parts of slots 26 extend and lifting the section free of posts 25.

In all of the figures of the drawings the spacing of baffle plates from the surfaces to be shielded and the spacing of baffles from each other are exaggerated for the sake of emphasis. In practice, only a very slight spacing is required so long as actual contact is avoided. This spacing may be of the order of $\frac{1}{2}$ ", a $\frac{1}{4}$ " or an $\frac{1}{8}$ inch, for example, depending upon the accuracy with which the baffle is held in spaced relation with 20 the surface to be shielded.

What I claim is:

1. Apparatus for effecting chemical reactions which comprises a casing providing a reaction chamber adapted to contain a contact or catalytic mass and a manifolding chamber adjacent one end of said reaction chamber, a perforated partition extending across said casing to separate said reaction chamber from said manifolding chamber, baffle plates of substantially non-absorbent material within said manifolding chamber extending over substantially the entire area of said partition and over that of at least those portions of the casing walls thereof located nearer to said partition, means holding said plates in spaced relation to said partition and said portions of said casing walls, thereby to shield said portions and partition against fluctuating temperatures of fluids passed through said manifolding chamber, and tubular means extending between said partition and baffle plate or plates adjacent thereto, in registering relation with the perforations in said partition and with oppositely located perforations in said baffle plate, so as to permit the passage of fluid between said 40 manifolding chamber and said reaction chamber without circulation thereof in substantial proportion through the spaces between said partition and the baffle plate or plates spaced in adjacent relation therewith.

2. Apparatus for effecting chemical reactions which comprises a casing providing a reaction chamber adapted to contain a contact or catalytic mass and a manifolding chamber adjacent one end of said reaction chamber, a perforated partition extending across said casing to separate said reaction chamber from said manifolding chamber, baffle plates of non-absorbent material within said manifolding chamber covering portions of the casing walls thereof adjacent said reaction chamber with a multiple layer of heat baffles, means spacing said plates or baffles from the portions of said walls which they shield and from each other, and less baffles covering other portions of said casing walls of said manifolding 60 chambers which are more remotely located from said reaction chamber, so that substantially all portions of said casing walls equidistant from said partition are substantially equally shielded and so as to shield most the said portions of the casing walls of said manifolding chamber which are adjacent said reaction chamber against fluctuations in the temperatures of fluids passed through said manifolding chamber, the edges of said baffles being fastened so as approximately 65 70 75

to exclude the circulation therebehind of fluids passing through said manifolding chamber.

3. Apparatus for effecting chemical reactions which comprises a casing providing a reaction chamber and a manifolding chamber adjacent one end of said reaction chamber, a perforated partition extending across said casing to separate said reaction chamber from said manifolding chamber, baffle plates within said manifolding chamber located adjacent but in spaced relation with the walls thereof to shield substantially the entire area of said partition and of the casing walls adjacent thereto against fluids of widely different temperatures passed through said manifolding chamber, said baffle plates being relatively arranged so as approximately to exclude the circulation therebehind of fluid passing through the manifolding chamber, a jacket surrounding said casing along said manifolding chamber, terminating adjacent the end of said manifolding chamber bounded by said partition, to form a confined passageway for heat exchange fluid surrounding said manifolding chamber, inlet and outlet ducts communicating through said jacket to permit circulation of fluid through said passageway, and tubular means extending between the aforesaid partition and baffle plate or plates adjacent thereto, in registering relation with the perforations in said partition and with oppositely located perforations or openings in the baffle plates, so as to permit the passage of fluid between said manifolding chamber and said reaction chamber while approximately excluding the circulation thereof through the space between said partition and the baffle plate or plates spaced in adjacent relation therewith.

4. In apparatus for effecting chemical reactions which comprises a casing providing a reaction chamber adapted to contain a contact mass and a manifolding chamber adjacent each end of said reaction chamber, one of said manifolding chambers being adapted to serve as an inlet manifold and the other as an outlet manifold, and perforated partitions separating each of said manifolding chambers from the adjacent reaction chamber, that improvement which comprises plate baffles of non-absorbent material located within each of said manifolding chambers and extending over and shielding substantially the entire surface of the perforated partition and at least those portions of the casing wall nearest to said partition in each of said inlet and outlet manifolding chambers, said baffles being located adjacent to but in spaced relation with the partition and walls which they shield and being constructed so as approximately to exclude fluids passing through each of the manifolding chambers from circulating through the spaces between the said baffles and the adjacent surfaces which they shield, thereby to minimize stresses in said casing walls and partitions by avoiding sharp fluctuations in the temperatures thereof and to prevent undue cooling or temperature change of adjacent sections of said reaction chamber, and tubular means extending between each of the said partitions and the respective baffles adjacent thereto, in registering relation with the perforations in each of said partitions and with oppositely located perforations or openings in the adjacent baffles so as to provide for the passage of fluid between each of said manifolding chambers and said reaction chamber without circulation thereof in large proportion through the spaces between either of said partitions and the respective baffles shielding the same.

5. Apparatus for effecting chemical reactions which comprises a casing providing a reaction chamber and a manifolding chamber adjacent one end of said reaction chamber, a perforated partition extending across said casing to separate said reaction chamber from said manifolding chamber, baffle plates within said manifolding chamber and located adjacent to but in spaced relation with the walls thereof to shield said walls against temperature changes from fluids of widely different temperatures passed through said manifolding chamber, said baffle plates being fitted together with respect to the walls of said manifolding chamber and to each other so as to provide a substantially continuous shield over said walls and so as approximately to exclude fluids from circulating past the edges thereof through the space between said baffle plates and the said walls which they shield, tubular means extending between said partition and the baffle plate or plates adjacent thereto, in registering relation with perforations in said partition and with oppositely located perforations or openings through said baffle plate or plates, so as to permit the passage of fluid between said manifolding chamber and said reaction chamber without circulation thereof in substantial proportion through the space between said partition and the baffle plate or plates spaced in adjacent relation therewith, and means including relatively small perforations or openings at spaced intervals in said baffle plates to permit a small proportion of the order of 1% to 2% of the fluid passing through said manifolding chamber to circulate through the space between said plates and the surfaces which they shield.

6. Apparatus for effecting chemical reactions which comprises an upright casing providing a reaction chamber and a manifolding chamber adjacent the lower end of said reaction chamber, a partition having perforations or openings therein extending across said casing to separate said reaction chamber from said manifolding chamber, baffles lining substantially the entire casing walls of said manifolding chamber, fastening means for holding said baffles firmly to said casing walls at a plurality of points located adjacent the upper end of said manifolding chamber, and combined spacer and fastening means adapted to join adjacent sections of said heat baffles in approximately fluid-tight engagement and maintain them in spaced relation to said casing walls.

7. A converter, a perforated partition therein dividing the interior into a reaction chamber adapted to contain a bed of contact or catalytic material and an end manifolding chamber, baffle plates mounted on the inside of the converter walls of said manifolding chamber, other baffle plates mounted upon the manifolding chamber side of said partition, the adjoining ends of all said baffle plates interfitting or overlapping in such manner as to provide a substantially continuous shield, which is held in spaced relation to the walls and partition defining said manifolding chamber, and a plurality of tubular means extending from the perforations or openings in said partition to said other baffle plates, in registering relation with perforations or openings in the latter, so as to permit the passage of fluid between said manifolding chamber and said reaction chamber without circulation thereof in substantial proportion through the spaces between said partition and the respective baffle plate or plates shielding the same.

8. A converter, a perforated partition therein

dividing the interior into a reaction chamber adapted to contain a bed of contact or catalytic material and an end manifolding chamber, members extending into said manifolding chamber from the converter walls and from said partition, baffle plates mounted upon said members in spaced superposed relation in such arrangement as to form a continuous shield about the interior of said manifolding chamber, cooperating means 5 on said members and on said plates permitting convenient detachment of the latter for removal or replacement, and tubular means extending from the perforations in said partition to the adjacent baffle plate or plates, in registering relation 10 with perforations or openings in the latter, so as to permit the passage of fluid between said manifolding chamber and said reaction chamber without the circulation thereof in substantial proportion through the spaces between said partition 15 and the respective baffle plate or plates shielding the same.

9. Apparatus for effecting chemical reactions which comprises a casing providing a reaction chamber and a manifolding chamber adjacent one end of said reaction chamber, a perforated 20 partition extending across said casing to separate said reaction chamber from said manifolding chamber, posts fastened to and extending inwardly from the walls of said manifolding chamber, a series of baffles, of heat resistant and non-absorbent material, mounted on said posts within said manifolding chamber adjacent the walls thereof, and extending over substantially the whole area of the walls thereof including that of 25 the said perforated partition, to shield the same against fluids of widely different temperatures passed through said manifolding chamber, said baffles being made up of a plurality of sections, fitted together and with respect to the said walls of said manifolding chamber so as to restrict circulation of fluid through the space between said baffles and the surfaces of said walls which they shield, each baffle being maintained in adjacent but spaced relation to the surfaces of said walls 30 which it shields, and tubular means extending between said partition and baffles adjacent thereto, in registering relation with the perforations in said partition and with oppositely located perforations in said baffles, so as to permit the passage of fluid between said manifolding chamber and said reaction chamber without the passage thereof in substantial proportion through the space between said partition and the baffle plate or plates spaced in adjacent relation therewith.

10. Apparatus for effecting chemical reactions which comprises an upright casing providing a reaction chamber and a manifolding chamber adjacent the lower end of said reaction chamber, a partition having perforations or openings therein extending across said casing to separate said reaction chamber from said manifolding chamber, baffles lining the casing walls of said manifolding chamber, fastening means for holding said baffles firmly to said casing walls at a plurality of points located adjacent the upper end of said manifolding chamber, combined spacer and fastening means adapted to join adjacent sections of said heat baffles in approximately fluid-tight engagement and maintain them in spaced relation to said casing, baffles shielding substantially the entire surface of said partition and held in spaced relation therewith, all of said baffles being arranged with relation to each other and to the surfaces which they shield so as to restrict circulation of fluid in the space between them and

the adjacent walls of said manifolding chamber which they shield, and tubular means extending from the perforations in said partition to the adjacent baffles in registering relation with openings in the latter, so as to permit the passage of fluid between said manifolding chamber and said reaction chamber without circulation thereof in substantial proportion through the spaces between said partition and the respective baffles shielding the same.

11. A converter, a perforated partition therein dividing the interior into a reaction chamber adapted to contain a bed of contact or catalytic material and an end manifolding chamber, members extending into said manifolding chamber from the converter walls and from said partition, baffle plates detachably mounted upon said members in such manner as to form a continuous shield about the interior of said manifolding chamber, at least a portion of said members being in the form of posts or studs with grooves at spaced intervals and certain of said plates having slots to provide slip and locking connections with said posts and to provide for mounting said plates in spaced superposition, and a plurality 15 of perforated conduits extending within said reaction chamber, said conduits each having an open end communicating with said manifolding chamber through the perforations of said partition, said open ends of said conduits extending 20 beyond said partition and through corresponding openings in said baffle plates adjacent thereto, so that fluids passing between said manifolding chamber and said reaction chamber do not circulate to substantial extent through the spaces between said baffle plates and said partition.

12. Apparatus for effecting chemical reactions which comprises a casing providing a reaction chamber and a manifolding chamber adjacent one end of said reaction chamber, a partition 25 having openings therein extending across said casing to separate said reaction chamber from said manifolding chamber, double or nested conduit assemblies extending within said reaction chamber, each conduit assembly comprising an insert or inner conduit and a surrounding outer conduit in spaced relation with said insert, the insert for each of said conduit assemblies being open at both ends and communicating with said manifolding chamber through one of the said 30 openings in said partition, said inserts or inner conduits projecting beyond said partition, baffle plates shielding substantially the entire area of said partition and fitting around said inserts so as not to obstruct the entry of fluids into said 35 inserts, said plates being of material which will not absorb liquids and which is heat resistant, and means for holding said baffles in spaced relation to said tube sheet.

13. Apparatus for effecting chemical reactions which comprises a casing providing a reaction chamber and a manifolding chamber adjacent one end of said reaction chamber, a partition having openings therein extending across said casing to separate said reaction chamber from said manifolding chamber, double or nested conduit assemblies extending within said reaction chamber, each of said conduit assemblies comprising an insert open at both ends and communicating with said manifolding chamber through one of the said 40 openings in said partition, said inserts or inner conduits projecting beyond said partition; baffle plates, of material which will not absorb liquids and is heat resistant, shielding substantially the entire area of said partition and fitting 45

around said inserts so as not to obstruct the entry of fluids into said inserts, baffle plates extending in adjacent but spaced relation with those portions of the casing walls bounding said manifolding chamber which are nearest to said partition, and means for holding all of said baffle plates fixedly in spaced relation with the said partition and walls which they shield, the edges

of said baffles being arranged relatively to each other and to the walls of the manifolding chamber so as approximately to exclude fluids passing between said manifolding chamber and said reaction chamber from circulating through the spaces between said baffle plates and the surfaces which they shield. 5

EUGENE J. HOUDRY.
